UNITED STATES PATENT OFFICE

LUCIAN BERNHARD, OF NEW YORK, N. Y.

DESIGN FOR AN UPHOLSTERED CHAIR

Application filed May 8, 1929. Serial No. 31,144. Term of patent 3½ years.

To all whom it may concern:

Be it known that I, LUCIAN BERNHARD, a citizen of Germany, residing at New York city, in the county of New York and State of New York, have invented a new, original, and ornamental Design for an Upholstered Chair, of which the following is a specification, reference being had to the accompanying drawing, forming part thereof.

I claim:

The ornamental design for an upholstered chair as shown.

In testimony whereof I affix my signature at New York city, New York.

LUCIAN BERNHARD.
